LEAKPROOF CARTON AND METHOD OF MAKING SAME

Robert E. Taggart, Appleton, Wis., assignor to American
Can Company, New York, N.Y., a corporation of New
Jersey

Filed June 6, 1962, Ser. No. 200,438
9 Claims. (Cl. 93—36.01)

This invention relates to an improved lined carton and method of making the same. More specifically, the invention may be used with particular advantage as a carton for packaging frozen foods which require a leakproof, sealed package.

Frozen foods such as strawberries are customarily packaged in a container employing either a separate moisture-proof liner, a bag or pouch, or else lined with a moisture-proof coating applied to the inner surface of the container. In the case of containers employing a separate liner, the liner is usually glued to the blank prior to erection of the carton and designed to fold with blank. Usually the lined containers render the container leakproof only to the upper edges thereof, and if the carton is turned upside down the liquid which serves as the packaging medium will leak out. Further, since the package is not hermetically sealed, the product is subject to desiccation upon prolonged contact with air. The above noted problems not only make handling more difficult but also produce a messy, unattractive package. If a separate filled pouch or bag is employed, valuable packing space is lost since the bag or pouch does not completely conform to the contours of the carton.

It is the purpose of the present invention to eliminate spoilage of packaged products by employing lined cartons in which the attached liner conforms completely to the inner surfaces of the carton. In addition the adjacent edges of the folded-over liner are sealed together to form an essentially airtight package. The invention is particularly advantageous since either locked or sealed cartons can be employed.

It is an object of the present invention to provide a completely moistureproof carton from an integral blank having a liner laminated thereto in selected areas.

Another object of the present invention is to provide an hermetically sealed carton which inhibits leakage of the packaging medium and desiccation of the product.

Yet another object of the present invention is to provide a simplified, efficient method, suitable for use with automatic machinery, for forming an essentially airtight, leak-proof package.

Still another object of the present invention is to provide a method for forming a carton having a receptacle portion and a cover portion, lining said receptacle portion with a deformable, heat sealable film material which has portions extending beyond the confines of the receptacle portion, filling said carton and sealing said carton to completely enclose the product in the film material.

According to the present invention, a completely leak-proof carton having receptacle and cover portions is produced by first setting up a blank either by locking or sealing flaps, then laminating a deformable, heat sealable film material to the inside of the cover portion as well as extending panels and flaps, lining said receptacle portion by stretching the film material into essentially complete con-

2

tact with the inner surfaces of said receptacle portions, filling, closing and sealing adjacent surfaces of said film material, and finally folding down and attaching the carton flaps and panels to provide a neat appearing, hermetically sealed carton.

Further details, advantages and objects of the invention will be apparent from the following specification and appended drawings wherein:

FIGURE 1 is a plan view of an integral blank suitably cut and scored to form a carton having a receptacle portion and a cover portion,

FIGURE 1a is an enlarged fragmental view of the portion of the blank enclosed by a broken line in FIGURE 1,

FIGURE 2 is a perspective view of the blank of FIGURE 1 set up,

FIGURE 3 is a diagrammatic representation of a preferred method of laminating a stretchable film material to the set up carton in a female die,

FIGURE 4 is a perspective view of the set up carton with the film laminated thereto,

FIGURE 5 is a sectional view of the carton in the female die as the film material is stretched down into the receptacle portion of the carton,

FIGURE 5a is an enlarged fragmental view of the portion of FIGURE 5 enclosed a broken line, including a portion of the blank and die, and showing the vacuum application channel,

FIGURE 6 is a perspective view of the carton with the cover portion folded to overlie the receptacle portion,

FIGURE 6a is a partial section of the carton taken along line 6a—6a of FIGURE 6,

FIGURE 7 is an end elevational view of the carton showing pressure applying means for heat sealing adjacent layers of film material together,

FIGURE 8 is a perspective view of the carton at a further stage of sealing,

FIGURE 9 is a perspective view of the carton of the completed carton,

FIGURE 10 is a plan view of a modified carton blank according to the present invention employing locking means, and

FIGURE 11 is a perspective view of the completed carton.

Referring first to FIGURE 1, the carton is made of a single foldable blank "A" of flexible material such as paperboard. The blank is divided by score lines 10-24 into hingedly connected panels and flaps including front cover panel 30, cover panel 31, rear panel 32, bottom panel 33, front panel 34, end cover panels 35, 45, glue flaps 36, 39, 41, 44, end panels 37, 42, edge flaps 38, 40 and 43. FIGURE 1a shows in detail holes 25 along score line 12 in the area indicated by the broken lines in FIGURE 1. Similar holes are located along the score lines 13, 17 and 21. The function of the holes will be described more fully hereinafter.

The blank has a thermoplastic adhesive preapplied thereon the stippled areas. Any adhesive which can readily be applied and is activated easily is suitable for use. Particularly suitable are wax based compositions employing any of a variety of additives including resins and polymers.

The blank "A" is formed into a carton by first applying adhesive to the outer surfaces of glue flaps 36, 39, 41 and 44 and infolding them about scores 20, 22, 18, and 16 respectively to form an angle of less than 90° with the panels

to which they are connected, i.e. 32 and 34. Rear and front panels, 32 and 34, are infolded about score lines 12 and 13, respectively, to positions at right angles with bottom panel 33. End panels 37 and 42 are then infolded about score lines 21 and 17 so that the inner end surfaces of the end panels become adhered to the adhesive-bearing surfaces of the glue flaps. Edge flaps 38, 40 and 43 are folded outwardly to lie in a common plane with cover panels 30, 31, 35 and 45 as shown in FIGURE 2.

The set up carton is then placed in a female die 59 as shown in FIGURE 3 and is passed under a heating element 57 to activate the preapplied adhesive. Located above the path of travel of the die 59 is a series of rollers 51, 52, 53 and 56. A roll of deformable heat sealable material 50 is mounted to unwind with the web passing around roll 51 and between a pair of nip rollers 52, 53 which provide a positive pulling action on the web to unwind it from the roll 50. After passing through the nip rolls the web passes over a support 54 whose edge coacts with cutting edge 55 to sever a sheet 58 from the traveling web. As the leading portion of the die 59 adjacent the front edge flap 40 passes under support 54, the leading edge of the web attaches itself to the activated adhesive-bearing surface of flap 40. The travel of the die 59 and the web of film material is regulated by means not shown so that the leading edges of the web and the flap 40 coincide. As the carton and film pass under the roller 56 the pressure laminates the film material 58 to the heat activated adhesive-bearing surfaces of the carton. The film is severed from the remainder of the web by cutting edge 55 when the trailing edge of front cover flap 30 is reached. The carton with the deformable, heat sealable sheet material attached is shown in FIGURE 4.

Thermoplastic deformable film materials having the desirable permeability and deformability characteristics include those well known in the art such as: rubber hydrochloride sold commercially under the trademark "Pliofilm"; polymers and copolymers of polyvinylidene chloride such as Cry-O-Vac and Saran; vinyl and vinyl copolymers or combinations; and polyester films such as Mylar. A highly preferred material is a laminate consisting of a polyethylene terephthalate (Mylar) approximately .0005" in thickness, laminated to a polyethylene film approximately .0025" in thickness.

FIGURE 5 illustrates the method by which the deformable, heat sealable film is forced down into contact with the surfaces of the receptacle portion. Initially, a pressure sealer 63 is applied to the upper surface of film sheet 58 on the portions overlying the area of cover panel 31 adjacent the receptacle portion and edge flaps 38, 40 and 43, sealing off the carton receptacle portion maintained in the cavity of the female die 59. A vacuum is then drawn through connecting channels 60, adjacent the bottom edges of the receptacle portion, and through channel 61 leading to the vacuum source. The vacuum is drawn through holes 25 in the score lines 12, 13, 17 and 21 causing the film material to depress until it conforms to the configuration of the inner surfaces of the receptacle portion. The broken lines of FIGURE 5 indicate the transition of the film from its upper horizontal position to the final depressed position. FIGURE 5a shows in detail the depressed film 58, the channels 60 and the hole 25 through which the vacuum is drawn.

Alternatively, the film can be forced down into the die cavity by air or gas pressure. In this method, the edges of the film sheet 58 adjacent the receptacle portion are again sealed off by pressure to prevent leakage. A pressing form 62 then descends on pressure sealer 63 forming another airtight seal. Air or gas under pressure is then forced down through the central shaft of the pressing form 62 depressing the film sheet 58 until it conforms to the configuration of the receptacle portion. In the methods described above the stretching of the

5 film sheet down into deep cavities in the die can be materially aided in the first instance by previously heating the sheet material and in the second instance by heating the air or gas. Depending upon the speed of operation and the amount of heat applied, heating element 57 which activates the adhesive may also serve to partially heat the film sheet, increasing its stretchability without tearing.

10 After the depression of the film sheet into the receptacle portion, cover panel 31 is infolded about score line 11 so that cover panels 30, 35 and 45 overlie edge flaps 40, 38 and 43, respectively, as shown in FIGURE 6. FIGURE 6a, which is a partial section of the carton shows edge flap 40 and superposed front cover panel 30 with adjacent layers of film sheet 58 interposed therebetween. The face to face film surfaces are then sealed together by the application of heat and pressure via heated bars 64 and 65. While upper bar 64 can be a flat solid plate, lower bar 65 must be U-shaped to conform to the configuration of three sides of the carton.

15 End cover panels 35 and 45 are then folded down against the underlying end panels 37 and 42, respectively, as shown in FIGURE 8. The closure is completed by forming triangular folds in the unsupported projecting portions of film sheet 58 while folding front cover panel 30 downwardly about score 10 to lie against front panel 34. The cover panels 30, 35 and 45 are readily sealed to the underlying front and end panels 34, 37 and 42, respectively, by means of the interposed heat sealable film material. Having been heated substantially by the bars 64 and 65 during the face to face sealing of the film, the film readily seals to the carton surface with the use of heat and pressure. The completed carton is shown in FIGURE 9. If desired, an adhesive may be employed 20 to implement the bonding of panels 30, 35 and 45 to the respective underlying panels in case the heat sealing properties of the film material to the paperboard should prove insufficient to produce the required bond.

25 As an alternative to the embodiment described above, the lined carton may be formed from a blank employing locking means for erection and closing. The modified blank "B" as shown in FIGURE 10 is divided by score lines 100-116 and cut lines 117 into hingedly connected panels and flaps including front cover panel 120, cover panel 121, rear panel 122, bottom panel 123, front 30 panel 124, end cover panels 125, 133, locking flaps 126, 129, end panels 127, 131, edge flaps 128, 130 and 132, and locking tab 134. Cut lines define female locking slits 138, 139, 140 and 142 which receive male locking tabs 137, 141, 136 and 135, respectively, as shown in FIGURES 10 and 11.

35 The blank "B" is formed into a carton by engaging locking tabs 137 in slits 138 and locking tabs 141 in slits 139. The set up carton is similar in appearance at this stage to the first embodiment shown in FIGURE 2. After erection, the carton is lined and the film material sealed by the method set forth in FIGURES 3-7 and the accompanying description. The closure of the carton is completed by folding the cover panels 120, 125 and 133 downwardly about score lines 100, 105 and 114 respectively. Male locking tabs 135 and 136 are inserted in female locking slits 142 and 140, respectively, to produce the completed closed carton shown in FIGURE 11. The adhesive, indicated by the stippled area in FIGURE 10, is purposely omitted from locking tabs 134, 135, 136 to prevent undesirable adhesion of the liner to the surfaces of these components of the carton. It is obvious, of course, that the particular configuration of the locking means can be changed as desired.

40 If desired, the cover panel may be omitted and a carton having side and bottom panels and edge flaps hingedly connected to the upper edges of the side panels may be employed. The sheet material is, then, adhered to all edge flaps and subsequently depressed into the receptacle portion in the manner previously described.

To close the carton after filling, the extended free end of the film is folded over to cover the receptacle and the edge flaps and adhered to the underlying film in the edge flap areas. The edge flaps are then folded down and sealed to the outside carton side panels as previously described. A significant saving in sheet material may be realized by a slight modification in the above procedure, in which the edge flap from which the free end of the sheet material extends is folded inwardly to partially cover the contents of the carton and the extended film then sealed to the remaining edge flaps in the regular manner. These flaps are then folded out and down to be sealed to the carton side panels as previously described.

The present invention provides a lined carton using a single blank and a single liner. The carton can readily be set up, lined, filled with the commodity to be packaged, and closed by automatic machinery. The contents are encompassed by an essentially airtight, leak-proof, hermetically sealed construction which insures freshness and retards spoilage. Both the size and configuration of the adhesive patterns used to heat seal the deformable, heat sealable film material to the carton blank can be varied as desired.

It is understood that the description of the carton construction given herein is merely illustrative of the essential features of the invention, and is not limited to the specific dimensions or contours, which may be greatly varied or modified and which variations are intended to be included within the scope of the appended claims.

I claim:

1. A method of forming from an integral carton blank an essentially hermetically sealed carton having a perforated bottom panel, hingedly connected side panels, and edge flaps hingedly attached to the upper edges of said side panels, which method comprises applying an adhesive to said edge flaps; setting up said blank to form a carton having the adhesive bearing surfaces of said edge flaps facing upwardly; attaching a deformable, heat sealable sheet material to the adhesive bearing surfaces of said edge flaps with said sheet material extending outwardly an appreciable distance from one side of the carton; depressing said sheet material into said carton to conform to the configuration thereof; folding over said extended sheet material and sealing the edges to the underlying portions of said sheet material which are adhered to said edge flaps.

2. A method of forming from an integral carton blank an essentially hermetically sealed carton having a bottom panel defined by perforated score lines, hingedly connected side panels, and edge flaps hingedly attached to the upper edges of said side panels, which method comprises applying an adhesive to one surface of each of the edge flaps; setting up said blank to form a carton having said edge flaps extending outwardly in a common plane and their adhesive bearing surfaces facing upwardly; adhering a deformable, heat sealable sheet material to the adhesive bearing surfaces of said edge flaps with said sheet material extending outwardly an appreciable distance from one side of the carton and being at least twice the size of the area defined by the outer edges of said edge flaps; applying pressure means to hold said sheet material in airtight contact, with the upper edges of said carton; depressing said sheet material into said carton to permanently conform to the configuration thereof; folding over said extended sheet material and sealing the edges to the underlying portions which are adhered to said edge flaps.

3. The method of claim 2 wherein said sheet material is depressed by gas under pressure directed down on top of said sheet forcing the air under said sheet outwardly through the perforations in said score lines.

4. The method of claim 2 wherein said sheet is depressed by a vacuum drawn through the surfaces in the score lines defining the bottom panel of the carton.

5. The method of claim 1 wherein said sheet material is depressed by gas under pressure directed down on top of said sheet material forcing the air under said sheet material outwardly through the perforations in the bottom panel.

6. The method of claim 1 wherein said sheet material is depressed by a vacuum drawn through the perforations in the bottom panel.

7. A method of forming from an integral carton blank 10 an essentially hermetically sealed carton having a bottom panel defined by perforated score lines, hingedly connected side panels, and edge flaps hingedly attached to the upper edges of said side elements, which method comprises applying an activatable adhesive to one surface of each of said edge flaps; setting up said blank to form a carton having said edge flaps extending outwardly in a common plane and having their adhesive bearing surfaces facing upwardly; passing said carton through means to activate the preapplied adhesive; adhering a deformable, heat-sealable sheet material to the upper adhesive bearing surfaces of said edge flaps with said sheet material extending outwardly an appreciable distance from one side of the carton and being at least twice the size of the area defined by the outer edges of said edge flaps; 15 applying pressure means to hold said sheet material in airtight contact with the upper edges of said carton; depressing said sheet material by means of a vacuum drawn through the perforations in said score lines into said carton to permanently conform to the configuration thereof; 20 folding over said extended sheet material; sealing the edges to the underlying portions adhered to said edge flaps; and folding down said edge flaps into engagement with said side panels and sealing them together by said heat-sealable material.

8. A method of forming from an integral carton blank an essentially hermetically sealed carton having a bottom panel defined by perforated score lines, hingedly connected side panels, and edge flaps hingedly attached to the upper edges of said panels, which method comprises 40 applying an adhesive to one surface of each of said edge flaps; setting up said blank to form a carton having the adhesive bearing surfaces of said edge flaps facing upwardly; attaching a deformable, heat-sealable sheet material to the adhesive bearing surface of said edge flaps with said sheet material extending outwardly an appreciable distance from one side of the carton; depressing said sheet material into said carton to conform to the configuration thereof by directing gas under pressure downwardly on top of said sheet material forcing the air under said sheet material outwardly through the perforations in said score lines; and folding over said extended sheet material and sealing the edges to the underlying portions of said sheet material which are adhered to said edge flaps.

9. A method of forming from an integral carton blank an essentially hermetically sealed carton having a bottom panel defined by perforated score lines, hingedly connected side panels, and edge flaps hingedly attached to the upper edges of said panels, which method comprises 50 applying an adhesive to one surface of each of said edge flaps; setting up said blank to form a carton having the adhesive bearing surfaces of said edge flaps facing upwardly; attaching a deformable, heat-sealable sheet material to the adhesive bearing surface of said edge flaps with said sheet material extending outwardly an appreciable distance from one side of the carton; depressing said sheet material into said carton to conform to the configuration thereof by drawing a vacuum through the perforations in the score lines defining the bottom panel of the carton; and folding over said extended sheet material and sealing the edges to the underlying portions of said sheet material which are adhered to said edge flaps.
